(No Model.)

F. X. GANTER

MACHINE FOR CUTTING THE METAL OF SHOW CASE MOLDINGS

No. 387,408.

Patented Aug. 7, 1888.

UNITED STATES PATENT OFFICE.

FRANCIS X. GANTER, OF BALTIMORE, MARYLAND.

MACHINE FOR CUTTING THE METAL OF SHOW-CASE MOLDINGS.

SPECIFICATION forming part of Letters Patent No. 387,408, dated August 7, 1888.

Application filed January 17, 1888. Serial No. 261,017. (No model.)

To all whom it may concern:

Be it known that I, FRANCIS X. GANTER, a citizen of the United States, residing at Baltimore, in the State of Maryland, have invented certain new and useful Improvements 5 in Machines for Cutting the Metal of Show-Case Moldings, of which the following is a specification.

My invention relates to a machine for cutting metal show-case moldings, and is illustrated in the accompanying drawings, in which—

Figure 1 is a vertical section of the machine. Fig. 2 is a top view of the machine. Fig. 3 is 15 a front elevation of the machine, in which certain parts are shown in section. Fig. 4 shows two views of the cutter-shaft drawn to a larger scale. Fig. 5 is a cross section of the feed-chute on line 5 5. Fig. 6 shows two views of 20 the cutter-plate on a larger scale. Fig. 7 is a top view of the cutter-plate and the cross-bar on which it is seated. Fig. 8 shows two views 25 of show-case molding, in which two pieces of molding, *a* *b*, are jointed together by the end of one piece, *b*, abutting against the side of the other. The abutting end of piece *b* is made to fit accurately against the side of piece *a* by being cut with the machine.

The show-case molding—such as may be 30 seen on the show-cases in drug and jewelry stores—is composed of wood covered by sheet metal, usually German silver. Heretofore in joining two pieces of this metal-covered molding, as shown in Fig. 8 of the drawings, the 35 fit of the jointed parts has been secured by the laborious operation of filing by a hand-file. The machine shown in the drawings is intended to do this work with accuracy and dispatch, and avoid the necessity of hand-filing referred to.

The letter *A* designates two standards; *B*, a cross-bar between them and secured to each standard by screws *c*. This cross-bar has in one side a recess, *d*, at the bottom of which is 45 a seat, *d'*, for the cutter-plate *e*, the cutting-edge *e'* of which is on top. To provide for the vertical adjustment of the cutter-plate *e*, two set-screws, *f*, pass up through the seat *d'* and bear on the bottom edge of the cutter- 50 plate, and two other set-screws, *f'*, enter laterally into holes *g* in the plate, and each screw projects through a vertical slot, *g'*, which

opens horizontally through the front of the recess in the cross-bar *B*. It will thus be seen the said set-screws *f* and *f'* enable the cutter-plate to be adjusted vertically to a nicety and hold it firmly. 55

The cutter *h*, which coacts with the cutting-edge *e'* on the plate, is on a rock-shaft, *h'*, which has bearings in a box on top of the two standards. The top of each standard forms the lower half, *i*, of the said box, and a half-tubular-shaped plate, *I*, forms the upper half. This top plate, *I*, extends entirely across the machine and covers the entire length of the cutter-shaft *h'*, except one end, to which a lever or arm, *k*, is attached, and by which the said cutter-shaft is rocked. This box has a Babbitt-metal lining, *l*, and the top plate is secured by the screws *m*. The top plate has 60 holes *n*, which provide for oiling the shaft 65 and bearing.

The cutter *h* is on the center of the shaft *h'*, and in the present instance is formed by removing a portion of the rounded side of the 75 shaft, leaving a flat surface, *h''*, whose edge *h* serves as the cutter. Thus the cutter *h* does not project beyond the plane of the rounded side of the shaft. By grasping the lever *k* the cutter-shaft *h'* may be rocked backward and forward in the box *I*, and thereby the two jaws of the cutter—to wit, the cutter *h* on the shaft and the edge *e'* on the plate—are made to coact. It is immaterial to the operation whether the cutter *h* is formed integral on the rock-shaft or not. As the top plate, *I*, of the box 80 covers the cutter-shaft *h'* over its central part, where the cutter *h* is, it prevents the cutter-shaft from springing or yielding when the cutters *h e'* are acting on the metal molding and 85 enables a small cutter-shaft, *h'*, to be used. 90

The top plate, *I*, of the box has at its center and front side a feed-inlet, *o*, to admit the end of the metal molding to the cutters.

The cutters *h e'* may vary in their shape or 95 configuration to be adapted to various designs of molding, and may have any shape that will best suit the particular design that is to be cut. The said cutters, therefore, are removable from the machine, and may be exchanged 100 for others at any time.

A feed-chute, *P*, supports the molding and presents it to the cutters properly. This chute has its end connected to the front of the cross-

bar by pivot-bolts q , which pass through the said end of the chute and through lugs q' on the cross-bar. A brace-rod, r , supports the chute. This brace-rod has its upper end jointed at s 5 to the chute and projects downward to and passes loosely through a roller, t , supported in bearings t' on the lower edge of the cross-bar B. A set-screw, u , in the said roller impinges against the brace rod r and holds it at any de- 10 sired point. It will be seen the pivoted chute P may be inclined to any desired extent. This is of importance, because the same cutters h e' will have a varying effect on the metal molding by changing the angle of inclination 15 at which the said molding is presented to the cutters. The same cutters may, by thus changing the inclination of the chute P , cut one design, b , of molding so that it will joint neatly and accurately with several other mold- 20 ings, a , each latter being of different design. The feed-chute has a stop-block, v , Fig. 2, provided with a set-screw, w . This stop-block serves to determine the exact length of the molding as it shall be cut by the machine.

25 This matching together of two pieces of molding I have here termed "jointing." It may properly be termed "miter-jointing" or "mitering," and the molding-pieces which form the joint may meet at any angle.

30 Having described my invention, I claim and desire to secure by Letters Patent of the United States—

1. A machine for cutting metal show-case moldings, comprising a cutter-plate, e , having an edge shaped to fit a design of molding, and a shaft, h' , mounted in suitable bearings, and

intermediate of its ends having a portion of its rounded side removed, whereat is a surface, h^2 , whose edge bisects the said rounded side and serves as a cutter, h , to coact with the 40 said cutter-plate.

2. A machine for cutting metal show-case moldings, comprising a cutter-plate, e , having an edge shaped to fit a design of molding, a shaft, h' , provided intermediate of its ends 45 with a cutter, h , which is the counterpart of the cutter-plate edge and which does not project beyond the plane of the rounded side of the shaft, and a box-bearing for said shaft, said box-bearing covering the shaft along its 50 length where the cutter is.

3. A machine for cutting metal show-case moldings, having in combination a cross-bar, B, provided with a recess, d , a cutter-plate, e , occupying the recess, a shaft, h' , provided in- 55 termediate of its ends with a cutter, h , which is the counterpart of the edge on said cutter-plate, and a box-bearing covering the entire length of the cutter-shaft.

4. A machine for cutting metal show-case 60 moldings, having in combination a stationary cutter-plate, e , a shaft, h' , provided interme- diate of its ends with a cutter, h , which is the counterpart of the edge on said cutter-plate, and a chute pivoted by one end adjacent to 65 the cutter-plate.

In testimony whereof I affix my signature in the presence of two witnesses.

FRANCIS X. GANTER.
